COMBINED REFRIGERATING COMPRESSOR
AND OIL SEPARATOR

Leonard F. Clerc, Detroit, Mich.

Application April 19, 1948, Serial No. 21,955

7 Claims. (Cl. 230—152)

1

This invention relates to compressors, and particularly to refrigerating compressors of the rotary type.

An object of the invention is to generally improve compressors, and to provide a device of the character indicated in which the entire compressor body, except a small surface at one end, is enclosed and hermetically sealed in a housing which forms an oil separator, a pressure equalizing chamber, and an oil reservoir.

Another object of the invention is the provision of a device of the character indicated, in which one of the principal parts of the device comprises an inexpensive casting in which is positioned hardened steel inserts which serve as wear resisting working parts.

A further object of the invention is to provide a refrigerant compressor in which the compressor body is formed of a casting having two principal sections, in one of which sections the compressor parts are assembled and housed, and in the other section is housed the drive shaft and shaft seal, whereby the shaft and shaft seal may be independently removed without disturbing the compressor proper.

Another object of the invention is the provision of a hermetically sealed compressor which is constructed and arranged so that it may be driven by an externally positioned motor.

Another object of the invention is the provision of a device of the character indicated, which is constructed and arranged so that the comparatively high internal pressures maintained therein serve to move the hermetically sealed parts into closer sealing relation with respect to each other.

Another object of the invention is the provision of a device of the character indicated which is constructed and arranged so that the rotor substantially floats freely on its drive shaft and between its defining side walls by virtue of the high pressures and the lubricating mediums provided therein.

Another object of the invention is the provision of a device of the character indicated, in which the compressed gases are discharged from the compressor tangentially into a chamber closely surrounding the compressor.

Another object of the invention is the provision of a device of the character indicated, which is constructed and arranged so that upon each revolution of the compressor rotor a predetermined amount of screened lubricating medium is injected under high pressures from the oil reservoir to and about all of the moving parts of

2

the compressor, thereby insuring a cushioning film of oil for the moving parts, and obviating the difficulty of an excessive amount of lubrication entering the compressor.

5 Another object of the invention is the provision of a device of the character indicated which is constructed and arranged so that during the operation thereof an effective oil seal is maintained between the moving and non-moving parts 10 of the compressor.

Another object of the invention is the provision of a hermetically sealed compressor which is constructed and arranged so that the oil seal assembly for the drive shaft may readily be removed from one end of the device without disturbing the working parts of the compressor.

Another object of the invention is the provision of a device which is constructed and arranged so that the lubricating medium is substantially removed from the compressed gases before the latter are discharged into the refrigerator line, thus obviating the difficulty of an excessive amount of lubrication being discharged into the high pressure line.

20 25 Another object of the invention is the provision of a device of the character indicated which is constructed and arranged so that the main body of the lubricating medium is prevented from entering the gas intake port of the compressor body.

30 35 Another object of the invention is the provision of a device of the character indicated, which is constructed and arranged so that the internal parts of the compressor receive a predetermined amount of a screened lubricant, which is injected into the area of the compressor defined by two vanes at the instant said area is on the low side of the compression cycle.

Another object of the invention is the provision 40 45 of a device of the character indicated, which is constructed and arranged so that there is an equalized pressure on all of the moving parts of the compressor at the moment of starting the compressor, thereby reducing the amount of power input necessary to initially move the compressor, and obviating the necessity of bucking a high head pressure upon starting.

Another object of the invention is the provision 50 55 of a vane type rotary compressor which is provided with means to positively reciprocate the vanes in the rotor slots, and means to relieve the back pressure in the rotor slots upon the inward stroke of each vane.

Another object of the invention is to provide 55 a vane type rotary compressor in which each

vane is provided with oppositely disposed rollers adapted to engage twin acting cam surfaces, whereby the vanes are positively reciprocated in the rotor slots, and whereby a predetermined clearance is maintained between the outer ends of the vanes and the rotor housing, which clearance is positively sealed by means of a lubricant.

Another object of the invention is the provision of a vane type rotary compressor which is constructed and arranged so that the vanes are free to float sideways within the rotor slots, whereby an equalized clearance may be maintained on opposite sides of said vanes by the internal pressure maintained in said device.

A further object of the invention is to provide a device of the character described in which the oil seal assembly for the drive shaft is mounted on the drive shaft between two main shaft bearings, whereby the oil seal is held in perfect alignment.

Another object of the invention is to provide a vane type rotary compressor in which the reciprocation of the vanes is positively controlled so that a predetermined clearance of close tolerance may be maintained at all times between the working parts, whereby when the device is connected in a refrigerating assembly the unit may be charged with a refrigerant through the low side without danger of forcing the lubricating oil into the refrigerator line.

Another object of the invention is to provide a device of the character indicated, which is constructed and arranged with a check valve in the suction side fitting of the compressor intake port, thereby eliminating the tendency of any liquified refrigerant to back into the suction line from the condenser when the compressor is idle.

Another object of the invention is to provide a device of the character indicated, which is constructed and arranged without a check valve on the discharge side of the compressor, thereby insuring an equalized pressure throughout the oil separator and the compressor when the compressor is idle, thereby eliminating the customary starting load and permitting the use of a low powered propulsion unit with its attendant economies.

Another object of the invention is to provide a refrigerant compressor which may be operated at a comparatively high speed with the result that a greater volume of gas may be compressed in a given period of time, with a substantial saving of motive power.

A further object of the invention is to provide a device of the character indicated, which is constructed and arranged so that the compressed refrigerant gases are discharged from the compressor into a chamber, whereby the gases are preliminarily cooled before being discharged into the refrigeration line, and whereby the temperature of the refrigerant is correspondingly reduced.

The foregoing and other objects and advantages of the invention will become more apparent as the description proceeds, reference being made from time to time to the accompanying drawings, forming part of the within disclosure, in which drawings:

Fig. 1 is a longitudinal sectional view of a device embodying the invention taken substantially on the line 1—1 of Fig. 2.

Fig. 2 is a section taken on the line 2—2 of Fig. 1.

Fig. 3 is a section taken through the liner ring, a perspective view of which is shown in Fig. 9.

Fig. 4 is a front view of one of the vanes.

Fig. 5 is a section taken on the line 5—5 of Fig. 4.

Fig. 6 is a perspective view of the casting comprising part of the compressor body.

Fig. 7 is a perspective view of the eccentric cam member.

Fig. 8 is a perspective of the front cam ring employed to form the outer guide surface for vane rollers and to form the front enclosure for the rotor.

Fig. 9 is a perspective view of the liner ring which serves to form the enclosure around the outer surface of the rotor.

Fig. 10 is a perspective view of the rotor with the vanes inserted with rollers.

Fig. 11 is a perspective view of the rear cam ring employed to form the outer guide surface for vane rollers and to form the rear enclosure

20 for the rotor.

Fig. 12 is a perspective view of the end closure cover for the casting shown in Fig. 6.

Fig. 13 is a perspective view of the drive shaft with the oil seal and end closure member in position.

Fig. 14 is a perspective view of the cylindrical housing which forms part of the oil separator, oil reservoir and pressure equalizing chamber.

Fig. 15 is a perspective view of the threaded 30 coupling which connects the cylindrical housing (Fig. 14) to the casting (Fig. 6) at the suction side of the compressor body.

Fig. 16 is a perspective view of the end closure cap for the cylindrical housing (Fig. 14).

Referring now more particularly to the drawings, it will be understood that in the embodiment herein disclosed, the reference character 20 (Figs. 1, 2 and 14) indicates a cylindrical housing which may be formed of a suitable length of heavy steel tubing, and to which is preferably secured, as by welding 21 (Fig. 1) the drilled and tapped bosses 22 and 23 (Figs. 1 and 2) to which are respectively connected the fittings 24 of the suction line 25 and discharge line 26 by means of machine bolts 27, or other suitable means. Gaskets 28 are provided between the bosses 22 and 23 and the fittings 24.

The cylindrical housing 20 is provided with a ring 29 (Figs. 1 and 14) which is welded into the 50 rear end, as at 30. The ring 29 serves as an abutment member for the casting flange 31 of the casting 32 (Figs. 1 and 6) so that during the operation of the device the casting 32 is pressed tightly against the flange gasket 33 (Fig. 1) by the internal pressure of the device which is a novel feature of the invention.

The casting 32 (Figs. 1 and 6) is provided with studs 34 which engage recesses 35 (Figs. 1 and 14) formed on the inside surface of the ring 29 and 60 serve as means to locate the casting 32 therein, and secure the casting 32 against rotation. The cylindrical housing 20 (Figs. 1, 2 and 14) is provided with supports 36 and an end closure cap 37 (Figs. 1 and 16) which is secured as herein-after described.

The casting 32 (Figs. 1, 2 and 6) is preferably made of a non-porous metal such as Mehinite and is provided with an extension member 38 (Figs. 1 and 6) which is drilled and tapped, as at 39, to accommodate machine screws 40 (Fig. 1) whereby the end closure member 41 (Figs. 1 and 13) is held in place and is secured tightly against the gasket 42 (Figs. 1 and 6) between the extension member 38 and the end closure member 41.

75 The casting 32 (Fig. 1) is provided with an

opening 43 which is adapted to accommodate the oil seal assembly 44 which is of special design, and which is also adapted to utilize the internal pressure of the device. The oil seal rear section 45 is pressed into place and abuts against a shoulder 46 formed on the end closure member 41, whereby it is held stationary while creating a sealing action between the surfaces of the oil seal rear section 45 and the front section 47 which revolves with the shaft 48. The seal assembly 44 is held in adjustable position by means of a spring 49 which in turn is held against longitudinal movement on the shaft 48 by a floating oil seal bushing 50, which abuts against the end surface of the high lead bronze bearing bushing 51, and seals it around the shaft 48. The shaft 48 is held in position by the shaft shoulder 52 which rides against the inner end face 52A of the rear high lead bronze bearing bushing 53. The oil seal assembly 44 may be removed and replaced at any time without disturbing the compressor.

The casting 32 (Fig. 1) is also provided with a peripheral opening 54, the lower part of which serves as an oil reservoir, the upper part of which serves as a refrigerant collector.

Radial bores 55 (Fig. 1) extend into the casting opening 43 so that lubricant may reach the working parts positioned on the interior of the casting opening 43. The casting 32 (Figs. 1 and 2) is provided with passageways 56 to maintain communication between the peripheral opening 54 and the oil separator and reservoir 57 which is formed between the end of the casting 32, the cylindrical housing 20, and the end closure cap 37.

A keyway 58 (Fig. 1) is formed in the front end of the casting 32, through which the casting is keyed to the eccentric cam member 59. The circular body 61 (Figs. 1 and 7) of the eccentric cam member 59 closes the end of the keyway 58 (Fig. 1) which leads to the enlarged opening 60 formed in the front end of the casting 32, which said enlarged opening 60 is adapted to accommodate the working elements of the compressor proper which I will now describe.

Mounted on a bearing bushing 51 (Figs. 1 and 7) is a hardened steel cam member 59 which consists of a circular body 61 and a collar member 62 which are formed integrally of a single piece of metal but machined so that the circular body portion 61 is eccentric to the circular member 62 portion. Positioned around the circular collar member portion 62 of the eccentric cam member 59 is a hardened steel, front cam ring 63 (Figs. 1 and 8) the inside diameter of which cam ring 63 is larger than the outside diameter of the circular collar member 62 of the eccentric cam member 59, whereby a raceway 64 (Figs. 1 and 2) is defined between the outer periphery of the circular collar member 62 and the inside periphery of the front cam ring 63 for the accommodation of rollers hereinafter described.

The rollers 65 and 66 and others (Figs. 1, 2, and 10) are mounted on each side of the roller spindles 67 and 68 which are formed as part of the vane 69 (Figs. 1, 2, 4, 5 and 10).

A cast iron liner ring 70 (Figs. 1, 2, 3 and 9) is mounted inside of the enlarged opening 60 (Figs. 1 and 2) and at one side engages the undercut portion 71 (Fig. 1) of the hardened steel front cam ring 63. The cast iron liner ring 70 (Figs. 2, 3 and 9) has an intake slot 72 and an exhaust slot 73. It will be noted, that the exhaust slot 73 is formed in an angular position extending outwardly from the inside surface of the cast iron liner ring 70 and terminates in a

narrow opening at the outer face of the cast iron ring 70 so that the compressed gases are discharged in a substantially tangential direction to the direction of rotation of the rotor 74, in the form of a fine vapor, which has a minimum of oil mixed therewith, and which is slightly precooled by its being discharged through the comparatively small exhaust port 73 into the larger area 57 of the oil separator, where some of the heat is dissipated through the oil separator housing.

The exhaust slot 73 (Fig. 2) communicates with an opening 75 formed in the top of the casting 32 through which the compressed gases enter the oil separator 57 (Figs. 1 and 2). As the compressed gases strike the deflector 76 the oil therein being heavier falls downward into the lower section of the oil reservoir 57 (Fig. 1) and the gases pass through the slot 77 into the peripheral opening 54 and hence out through the discharge port 78 and into the pressure line 26 through the fitting 24.

The rotor 74 (Figs. 1, 2 and 10) is a comparatively narrow Mehinite cast iron circular member having a hexagonal central opening 79 adapted to engage the hexagonal end 80 (Figs. 1 and 13) of the shaft 48 so that the rotor 74 (Fig. 1) may be rotated with the shaft 48. The shaft 48 is directly driven by a motor (not shown) or by a pulley 81 which may be belted to a motor (not shown).

An important feature of the invention resides in the fact that the rotor 74 (Fig. 1) is mounted on the double bearinged shaft 48 in such manner that it may freely float axially on the shaft 48, so that it tends to automatically center itself between the front and rear cam rings 63 and 82 under the influence of the internal pressure maintained in the device.

The rotor 74 (Figs. 2 and 10) is also provided on each side with concentric grooves 83 which are spaced from the outer periphery of the rotor 74, and assists in the lubrication of the device as hereinafter described.

Apertures 84 and 85 (Figs. 2 and 10) extend through the rotor 74 and communicate at either side thereof with the concentric grooves 83. The grooves 83 and the apertures 84 and 85 communicate with aperture 86 (Figs. 1 and 11) which is formed in the hardened steel rear cam ring 82, and also communicate with an aperture 87 (Figs. 1 and 12) formed in the end closure cover 88 which is drilled and tapped, as at 89 (Fig. 1) to accommodate the oil tube fitting 90 to which is secured the tube 91 which extends downwardly well below the oil level 92 of the device into a fine screen oil protector 93, whereby a metered amount of screened oil from the oil reservoir 57, which is under high pressure, is shot into the fine screen oil protector 93 hence into the tube 91 and discharged through the cover aperture 87 into the aperture 86 and into the compressor as each aperture 84 and 85 of rotor 74 passes the aperture 86. This insures an even distribution of oil to both sides of the rotor 74 and assists in the proper lubrication of the vanes 69.

Each vane 69 and others not specifically given reference characters, are formed as shown in Figs. 4 and 5 with integral spindles 67 and 68 and angular end faces 94, so that during the sweep of the vanes 69 (Fig. 2) around the inside surface of the cast iron liner ring 70, there is always an accumulation of oil picked up just ahead of each vane 69, this insures a frictionless oil seal between the angular end face 94

of the vane 69 and the inner periphery of the cast iron liner ring 70.

The rotor 74 (Figs. 2 and 10) is provided with radial slots 95 in which are adapted to reciprocate the hardened steel vane 69 and the other vanes which are not specially numbered. The vanes 69 are formed as shown in Figs. 4 and 5, and are also provided at the front and rear surface with relief pressure grooves 96 so that oil may reach each working surface of the vanes 69 (Fig. 2) and the rotor radial slots 95. The grooves 96 also serve to relieve the gas and oil pressure created between the end of the vanes, 69 as at 97, on their inward stroke. This greatly reduces the power required to rotate such a device, at the same time supplying through the bores 98 formed in the rotor 74 an oil film to each inner working surface of the hexagonal central opening 79 (Fig. 1) and hexagonal surfaces of the end 80 of the shaft 48.

The rollers 65 and 66 and others not specifically numbered (Figs. 1 and 2) are positioned to revolve on the integral roller spindles 67 and 68, and travel in the raceways 64 and 105. An oil film is always maintained between the working faces of the rollers 65 and 66 and the inner face of the circular collar member 62 and outer periphery 104 of the hardened steel bushing 103, and the faces 99 of the front and rear hardened steel cam rings 63 and 82. An oil film is also maintained between the ends of the vanes 69 and the cast iron liner ring 70, whereby their clearance is sealed.

The hardened steel rear cam ring 82 (Figs. 1 and 11) is similar to the hardened steel front cam ring 63 (Figs. 1 and 8) except that it has the aperture 86 (Figs. 1 and 11) and it is reversed whereby its shoulder 100 is adapted to engage the opposite side of the cast iron liner ring 70, as at 101.

The casting 32 (Figs. 1 and 6) is provided with an end closure cover 88 (Figs. 1 and 12) having an inturned hub 102 which is provided with a hardened steel bushing 103 pressed thereon. The outer periphery 104 (Fig. 1) of the hardened steel bushing 103, together with the inner periphery of the hardened steel rear cam ring 82 form the rear raceway 105 for the rollers 66.

The end closure member 88 (Figs. 1 and 12) is provided with bolt holes 106 and locating lugs 107, which are adapted to engage recesses (not shown) formed in the casting 32 (Fig. 1). The end closure member 88 is secured to the casting 32 by means of machine screws 108 which engage the drilled and tapped holes 109 formed in the casting 32.

The end closure cup 37 (Figs. 1 and 16) is provided with a central opening 110 (Fig. 1) and a threaded hub 111 which is welded thereto, as at 112, and through which is extended a long machine bolt 113 adapted to contact and put pressure on the end closure member 88 of the casting 32. The end of the long machine bolt 113 is welded over, as at 114, and the end closure cap 37 is welded, as at 115, to the cylindrical housing 20.

The high pressure created within the device between the end closure member 88 and the end closure cap 37 will exert an even pressure against the end closure member 88 thereby forcing the end closure member 88 tightly against the end of the casting 32, which in turn will press the casting flange 31 against the flange gasket 33 which in turn will be pressed tighter against the ring 29 of the cylindrical housing 20 to seal the

parts. This is an important feature of the invention.

The cylindrical housing 20 (Figs. 2 and 14) is secured to the casting 32 (Figs. 2 and 6) by means of a threaded coupling 116 (Figs. 2 and 15) which extends through the coupling port 117 (Figs. 2 and 14) of the threaded boss 22 of the cylindrical housing 20 and is threaded into the suction port 118 (Figs. 2 and 6) of the casting 32.

A gasket 28 surrounds the opposite end of the threaded coupling 116, as at 119. A fine oil screen 120 is inserted into the end of the threaded coupling 116 and when the fitting 24 is drawn down tightly by the machine bolts 27 the fine oil screen 120 is imbedded into the gasket 28 and the gasket 28 seats and seals its self tightly between the outer end of the coupling port 117 and the opposite end of the threaded coupling 116.

A conventional check valve (not shown) is provided at any suitable place on the suction side of the device, but I prefer not to employ a check valve on the pressure side of the device for the reason that it is desirable when the device is idle to maintain the same pressure throughout the compressor and oil separator as is maintained in the condenser and receiver (not shown). This provides a distinct advantage in the operation of the device in that the compressor can again be started without bucking a head pressure.

Having described my invention, what I claim and desire to secure by Letters Patent is:

1. In a device of the character described, a casting having a central passageway, counter-bores at each end of said passageway, end closure members for said counter-bores, a shaft extending through one of said end closure members and through said passageway and into the opposite counter-bore, a rotary compressor assembled in said last named counter-bore and arranged to be driven by said shaft and a gas tight housing enveloping all but one side of said casting, said casting being provided with a peripheral cut-out area concentric with one of said counter-bores, said cut-out area defining a portion of a gas collecting space at the top and an oil collecting space at the bottom of said casting, there being a restricted passageway through said casting between said oil and gas collecting spaces and said last named counter-bore, there being a pump discharge opening in said casting in communication with said oil and gas collecting space, whereby oil is forced through said restricted passageway into said first counter bore, and there being a discharge opening in said enveloping gas tight housing above and in communication with said gas collecting space.

2. In a device of the character described, a casting having a central passageway, counter-bores at each end of said passageway, end closure members for said counter-bores, a shaft extending through one of said end closure members and through said passageway and into the opposite counter-bore, a rotary compressor assembled in said last named counter-bore and arranged to be driven by said shaft and a gas tight housing enveloping all but one side of said casting, there being a substantially large reservoir adapted to hold oil and refrigerant formed between one of said end closure members and said gas tight housing, a pump discharge opening communicating with said reservoir, there being a restricted passageway through said last named end closure member and communicat-

ing between said reservoir and the interior of said counter-bore containing said compressor assembly, at a point above the oil level in said reservoir, whereby metered amounts of oil are withdrawn from said reservoir and discharged into the counter-bore containing the rotary compressor upon each revolution of the rotor of said compressor.

3. In a device of the character described, the combination of a body having a central longitudinal opening, a large and a small counter-bore in said opening, a drive shaft in said opening and having one end extending outside said body, an eccentric cam member on said shaft, double bearings in said body for said shaft, a hardened steel liner ring in said large counter-bore, said ring having intake and exhaust passageways therein, flanged rings cooperating with said liner ring to form a closed compartment in said body, a rotor slidably mounted at one end of said shaft and rotatable thereby in said closed compartment, radial slots in said rotor, vanes slideable in said slots, rollers carried by said vanes and arranged to be guided in part by said flanged rings and said eccentric cam, an end closure member for said body having a hub arranged to help guide said rollers, and a gas tight housing enveloping said body but spaced therefrom throughout a substantial area of said body, said housing having a discharge opening above said small counter-bore and a deflector on its inside wall above and in spaced relation to the exhaust passageway in said liner ring, and an outlet in said body from said large counter-bore in communication with the exhaust passageway in said ring. 35

4. The combination defined in claim 3, in which said housing is provided with an abutment ring arranged to be contacted by one end of said body, whereby upon the increase of pressure within said housing said body is brought into closer contact with said ring to effect a seal therebetween.

5. The combination defined in claim 3, in which said body is provided with a peripheral cut away portion, which together with the housing defines an oil and gas collector area.

6. The combination defined in claim 3, in which said body is provided with a peripheral cut away portion, which together with the housing defines an oil and gas collector area.

7. The combination defined in claim 3, in which said housing has an intake opening in direct communication with the intake passageway in said liner ring.

LEONARD F. CLERC.
